UNITED STATES PATENT OFFICE.

FERDINAND A. RUDOLF, OF NEW YORK, N. Y., ASSIGNOR TO NICHOLS COPPER COMPANY, OF NEW YORK, N. Y., A CORPORATION OF NEW YORK.

ELECTRODE.

1,267,120.

Specification of Letters Patent. Patented May 21, 1918.

Continuation in part of application Serial No. 65,008, filed December 4, 1915. This application filed August 15, 1916. Serial No. 114,945.

To all whom it may concern:

Be it known that I, FERDINAND A. RUDOLF, a citizen of the United States, and a resident of Queens, borough of Queens, city of New York, State of New York, have invented certain new and useful Improvements in Electrodes, of which the following is a specification.

My invention relates to electrodes for use in the electrolytic refining of metals, such as the electrolytic refining of copper and has particular application to such refining by the well-known series system in which the electric current passes through a suitable electrolyte from the anode side of each of a row of plate electrodes to the cathode side of the next plate in the row. As a result metal, say copper, is removed from the anode side of each plate and is deposited on the cathode side of the next plate. In practical electrolytic refining the electrodes are impure at the beginning of the process, copper electrodes, for example, containing usually silver and gold together with impurities which are relatively valueless. The current strength employed is adapted to deposit pure copper while leaving behind the gold and silver and other impurities. These impurities, detached from the anodes, descend by gravity through the electrolyte toward the bottom of the tank and are collected therefrom in the form of a slime and treated to recover their values. This separation of pure copper from the impurities of the electrodes is, however, imperfect in practice because a certain proportion of the impurities come into contact by diffusion or otherwise with the cathode sides of the plates in the neighborhood of the plates from which they were released and are deposited thereon, with the result that the copper deposit is not pure and the recovery of precious metal values from the slime is inefficient. The occlusion of these slimes by the cathodes, moreover, results in rougher deposits than are desired.

One of the objects of my invention is to provide suspended electrodes of such construction that such loss of precious metal values in the refining process is practically eliminated and the deposit of the desired metal is substantially pure. Another object

is to provide electrodes suspended in such a manner as to be inclined slightly, the upper sides thereof forming the anodes and the lower sides thereof forming the cathodes. Other objects of my invention will be pointed out or will otherwise appear in the following description of my invention in the embodiment thereof shown in the accompanying drawings.

This application is, in greater part, a division of an application entitled "Electrodes" filed by me December 4, 1915, Serial No. 65,008.

In the drawings, Figure 1 is a longitudinal, vertical section of an electrolytic tank containing a row of electrodes formed and supported in accordance with my invention;

Fig. 2 is a plan view of a portion of the tank and electrodes of Fig. 1;

Fig. 2^a is a plan, similar to Fig. 2 but enlarged, showing the arrangement of tank and electrodes of Fig. 1 but with a modified form of supporting ledge;

Fig. 3 is a detailed side elevation of a modified form of my invention;

Fig. 4 is a detail front elevation of said modified form; and

Fig. 5 and Fig. 6 are cross sectional views of further modified electrodes.

The electrolytic tank 9 shown in Fig. 1 may be of the usual form and proportions and may be composed of any suitable and known materials. The upper portion of each of the side walls is provided throughout its length with an internal support or ledge 10 upon which the electrodes 11 are adapted to be supported. The side walls extend upward above said ledge so that the level of the electrolyte may be maintained above said ledge. The electrodes 11 each comprises a flat plate provided with supporting lugs 12 at the upper sides of the plate, said lugs extending laterally beyond the edges of the plate and being bent to one side of and at an angle to the plate, the under edges of the lugs being supported upon the tank ledges 10. A part of the under portion of each of these lugs 12 is cut away to form an extension 13 separated from the ledge 10 whereby the extensions form handles which may be utilized for introducing the electrodes into the tank and removing them therefrom.

The level of the electrolyte in the tank is preferably maintained substantially along the line A—B.

The electrodes are placed, as shown, parallel to each other supported upon the ledge 10 and evenly spaced apart. The supporting lugs being bent away from the plane of the body of the electrode, and being adapted to form the points of support for the electrode, it will be seen that they operate to bring the point of support outside of the longitudinal plane of the electrode, which plane passes through the center of gravity thereof, thus causing the electrode to assume a position inclined with respect to the vertical. When so positioned, the anode side is uppermost and the cathode side is below. The impurities including the precious metals are released at the anode side and become detached in the form of slime and slide down upon this side of the plate to the bottom edge thereof from which they drop to the bottom of the tank. The impurities are thus guided in their downward course so that substantially no part of them will diffuse in suspended form through the electrolyte between the plates, and come into contact with or become occluded by the cathode side of the next plate, as often happens when the usual vertically supported plates are employed. The inclination of the cathode makes it difficult for any slime which may be in suspension to come into contact therewith; the inclination of anode prevents free diffusion of the impurities and guides them in substantially unsuspended form to the bottom edge of the plate.

The action of electrolysis removes metal from one side of each electrode and deposits pure metal upon the other side thereof, the original electrode thus becomes thinner and thinner as the process goes on. Because of the fact that the electrode is wholly submerged in the electrolyte this process goes on with respect to the whole of the plate. The structure, therefore, does not become weakened as would be the case were the level of the electrolyte maintained below the top of the plate, say, below the supporting ears thereof. In such case it is obvious that the plate becomes greatly weakened at or near the electrolyte level, so that before the time required for a practically operative process has elapsed, the weakening of the plate at this point will have developed to such an extent that the weight of the plate below this point will cause a bending or buckling and the plate will assume a vertical position. It will be seen that such a circumstance will result in the formation of short circuits or uneven deposition or will otherwise render the process practically inoperative. This defect of inclined suspended plates has been effectively overcome by totally submerging the electrodes in the electrolyte. I do not,

however, claim this total submergence of the electrodes as part of my invention and it is, in fact, the invention of another.

A modified form of my invention is illustrated in Figs. 3, 4, 5 and 6. The plate shown in these figures is in the form of an arch. It may be smoothly curved in arch form as shown in Figs. 3 and 4, in which case the curve may be an arc of a circle, ellipse or any other suitable curve; or it may be angularly bent in arch form as shown in Figs. 5 and 6, in which case the flat portions unite with each other to produce an arch structure. The plate may, of course, be formed by a combination of curved and flat portions, whereby an arched structure is produced.

The plate 14, Figs. 3 and 4, is provided with suitable lugs 15 at the top sides thereof, said lugs having a lower supporting edge 85 with which the rings 16 are adapted to engage. These rings are themselves supported by cross bars 17 which extend across and are supported by the tops of the side walls of the tank; the latter may or may not be provided with the ledge shown in Fig. 1. The plates 18 and 19 shown in Figs. 5 and 6 respectively may be supported similarly to the plates 14 or similarly to the plates 11, as desired.

When the plates are supported by rings as shown in Figs. 3 and 4, the level of the electrolyte may be substantially along the line C—D. After the plate has been subjected for some time to electrolytic action, it will become relatively thin in the neighborhood of the line defining the level of the electrolyte. Owing to the fact that the plate is arched, however, this thinning of the metal does not weaken the plate so that it will bend toward the vertical position.

In the case of the arched plates as well as in the case of the flat plates having supporting lugs as described, the point of suspension is outside of that longitudinal plane 110 of the plate, which is parallel to the tangential plane at the center line of the plate, which longitudinal plane passes through the center of gravity thereof. Thus when plates of either design are suspended, the bodies 115 of the plates will automatically incline at an angle to the vertical and the beneficial results of such inclination will be attained.

If desired, the plates may be supported by inserting the lugs or ears in suitably 120 shaped shoes of any non-corrosive and dielectric material.

When the ledges 10 are employed to support the electrodes, it may happen that, in the course of time, a sufficient amount of 125 slimes may lodge upon the top of the ledges to short circuit the plates. This may be avoided, in large measure at any rate, by forming recesses or depressions in the top edge of each ledge between the electrodes, 130

as shown at 20, Fig. 2^a. These depressions or recesses may, if desired, be slots passing completely through the ledge from top to bottom, thus virtually substituting a series 5 of independent blocks for a straight ledge, or, slips or wedges may be arranged to project upwardly from the ledges between the electrodes, thus splitting the slimes and breaking their continuity between electrode 10 and electrode. Such slips or wedges I regard as equivalents of the referred to depressions, recesses or slots.

Having described my invention, I claim:

1. In combination, a longitudinally arched 15 electrode and means engaging therewith in proximity to the lateral top edges thereof from which the electrode freely hangs for suspending said electrode with its longitudinal axis at an angle to the vertical.
- 20 2. An electrode comprising an arched plate provided with a supporting hook in a plane other than the longitudinal plane of the plate which is parallel to the tangential plane at the center line of the plate, which longitudinal plane passes through the center 25 of gravity thereof.
3. In combination, a longitudinally arched electrode and means engaging therewith above its center of gravity for suspending 30 said electrode with its longitudinal axis at

an angle to the vertical, there being no support for the electrode below its center of gravity.

4. In combination, an electrolytic tank adapted to hold electrolyte, a plurality 35 of longitudinally arched electrodes contained therein and supporting means engaging each electrode above its center of gravity and from which the electrode is freely suspended clear of the tank with its 40 longitudinal axis inclined to the vertical.

5. In combination, an electrolytic tank adapted to hold electrolyte and having ledges on opposite walls to support electrodes, and electrodes having laterally ex- 45 tending lugs adapted to rest upon said ledges, there being depressions in the top edges of the ledges between neighboring electrodes.

6. In combination, an electrolytic tank 50 adapted to hold electrolyte, a plurality of longitudinally arched electrodes contained therein, and supporting means for each electrode from which the electrode hangs free, said means engaging the electrode above the 55 center of gravity thereof and laterally of its longitudinal center line.

In testimony whereof I have hereunto set my hand.

FERDINAND A. RUDOLF.
